UNITED STATES PATENT OFFICE.

CHARLES OWENS, OF CHATTANOOGA, TENNESSEE.

PROCESS OF CRACKING OIL.

Application filed May 28, 1921, Serial No. 473,246. Renewed April 1, 1926.

My invention is a modification of my pending application (Serial No. 346,721, filed Dec. 22nd, 1919, gas producing attachment for internal combustion engines) as it relates to the refining of oils, i. e., separating of oils into different grades, cracking oils of a heavier specific gravity into lighter, more volatile oils, and also for breaking up oils into permanent gases, when so desired.

10 An apparatus embodying the invention is shown in the accompanying drawing, in which:

Figure 1 is a diagram with a portion of the apparatus in section; and

15 Fig. 2 is a sectional view of a portion of the apparatus.

In this drawing, 1 is a steam boiler from which steam is delivered through a pipe 2 to a mixer 3 to which oil is delivered from an oil tank 4 through pipe 5, pump 6, pipe 7, supply bowl 8 and pipe 21 to openings 23 of a Venturi nozzle 20. The oil supplied is regulated by an adjustable needle valve 22, and any excess oil reaching the bowl 8 will 25 pass back to the tank 4 by the overflow pipe 9. The steam reaches the venturi at substantially atmospheric pressure, for which purpose the pipe 2 is open to atmosphere at 2' and both the steam boiler and the oil tank are open to the atmosphere. The venturi is subjected to vacuum depression in 30 pipe 10 into which pipe the mixture of oil and steam is delivered after leaving the venturi. This vacuum depression is induced by

35 a vacuum pump 19 interposed between the two last condensing tanks so as to subject the cracked products to atmospheric or higher pressure as an aid to condensation in the recovery of the oil in the last tank or 40 tanks, i. e., it is drawn by vacuum through the tanks as far as the pump 19, and from there on it is forced forward by the compression action of the pump. The pipe 10 connects with a heating coil 11 in a furnace 12 so that the mixture of oil and steam passing 45 through this coil is subjected to heat. This coil connects by pipe 13 with condenser 14. There may be any required number of these condensers as shown at 15 and 16 and the 50 last one connects by pipe 18 with the suction pump 19. At 17 I show draw off cocks.

In the operation of the system the furnace 12 is heated to say 750° to 950° F. and the 55 boiler 1 is heated to deliver steam to the venturi 20. The vacuum pump 19 and oil pump 6 are then started. The vacuum depression draws the steam through the venturi and the velocity of the steam passing 60 through the restricted bore of the venturi draws oil from the bowl 8 through the series of ports 23 leading from the annular space or chamber 3' as a result of which the oil is divided, and becomes thoroughly mixed with 65 the steam, which mixture enters the pipe 10 in the form of spray. The mixture under the suction of the pump 19 then passes through the oil cracking coil 11 and into the condensers where the different grades of 70 oil are separated out from the mixture and are recovered through the cocks 17.

Principles entering into and influencing the cracking and refining of the oil in my vacuum oil cracking and oil refining process 75 are as follows:

The presentation of two nonmiscible elements to heat, lowers the boiling temperature below that required when either element is presented singly:

80 The boiling point of oil under vacuum is lower than the boiling point at atmospheric pressure:

The separating action of a vacuum on molecules:

85 The separating action of heat on the elements of which oil is composed.

Because of the foregoing facts it is my belief that the action of the vacuum in conjunction with the steam in the presence of 90 heat produces the following results:

(a) Presents the oil and steam in a thoroughly mixed condition, in suspension, to the heat, in finely divided particles.

(b) Maintains the finely divided oil and 95 steam, in suspension, in a thoroughly mixed condition.

(c) The steam serves to atomize and feed the oil and serves as a carrier for the finely divided oil until the separation of, and re- 100 association of the elements occurs.

I claim:

A process of treating hydrocarbon oil which comprises drawing hydrocarbon oil

into an atomizer by means of steam at substantially atmospheric pressure, atomizing said oil by said steam, drawing said atomized oil and steam into a heating zone maintained at a cracking temperature, maintaining sufficient suction on said atomizer and heating zone to draw said steam at atmos-

pheric pressure, into said atomizer and said atomized oil and steam into and through said heating zone, and condensing the resultant vapors.

In testimony whereof, I affix my signature.

CHARLES OWENS.
